UNITED STATES PATENT OFFICE.

EVALD J. ENGMAN, OF ST. BERNARD, OHIO.

CANDLE-FINISHING MACHINE.

Application filed June 28, 1923. Serial No. 648,192.

To all whom it may concern:

Be it known that I, EVALD J. ENGMAN, a citizen of the United States, and residing at St. Bernard, in the county of Hamilton and State of Ohio, have invented a new and useful Improvement in Candle-Finishing Machines, of which the following specification is a full disclosure.

This invention relates to improvements 10 in candle finishing machines in which the candles, after being molded, are drawn through heated finishing dies, during which operation superfluous material is removed, and the candles smoothed and given uniform dimension. The invention herein is 15 particularly directed to improved mechanism for drawing the candles through the dies, and includes two reciprocable mutually counterbalanced frames having hooks, upon 20 which the candles are adapted to be hung, and thereafter drawn slowly through the molds.

An object of the invention is to simplify 25 the structure and increase efficiency of operation, by providing means for starting either frame upwardly from its lowermost position after the candles have been suitably connected therewith, to draw the candles slowly through the dies, and also providing means for automatically stopping 30 each frame or carriage in its lowermost or loading position.

Another object is to conserve operating 35 power by mounting the two frames in mutually counterbalanced relation, one frame being connected at each end of a flexible drive element, which element is engaged over, suspended from, and ~~connected~~ by a companion drive element upon an 40 intermittently and periodically rotatable shaft.

Another object of the invention is to provide 45 for a relatively slow motion or rate of travel of the frames.

Another object of the invention is to provide 50 a finishing die, by the use of which superfluous material will be positively removed from the candle, and from the finishing die after the candle is drawn therethrough, producing a finished candle and insuring clean dies after each drawing operation.

Another object is to provide reciprocable 55 candle carrying members operable from a common reversible power shaft, and suspended at opposite sides of said shaft and

upon a drive element operable by said shaft, the frame suspending element being of such length that the ends of the candle hooks of one frame will be disposed beneath 60 the chamber with their shanks traversing the dies, when the ends of the candle hooks of the other frame are spaced a substantial distance above the chamber in such manner that the lower ends of candles suspended 65 thereon will clear the dies. Thus, when one frame is in its lowermost position, the other will be in its uppermost position.

Other objects and certain advantages will be disclosed in the description of the drawings forming a part of this specification, in which drawings:

Figure 1 is a front elevation of my improved candle finishing machine;

Figure 2 is a side elevation, with a 75 diagrammatic representation of the electrical apparatus connected with, and operable by the machine for machine control;

Figure 3 is a fragmentary vertical section on line 3—3 of Figure 1;

Figure 4 is a horizontal section on line 4—4 of Figure 1; and

Figure 5 is an enlarged detailed transverse section through the heating chamber and one of the improved dies.

The device or machine herein comprises a hollow rectangular casing 1 as a heating chamber, the casing having formed integral therewith a plurality of vertically disposed guide tubes 2, as die holders, traversing the 90 chamber from top to bottom and arranged in rows. The chamber is provided at its bottom with inlet and outlet pipes 3, 4, by which steam or hot water is introduced into and allowed to escape from the chamber, to heat the tubes 2 and improved dies 10 disposed therein. Mounted upon the casing are guide rods, respectively 5, 6 arranged in pairs, said rods being in vertical parallel relation, and each pair being op-

posingly placed centrally of adjacent rows of dies 10, see Fig. 4. Slidably mounted upon the rods 5 is a frame 7, and upon the rods 6 a frame 8, each frame being connected at one end of a sprocket chain 9, which is engaged with a sprocket wheel 9^a mounted on a suitable horizontally disposed shaft 11, as an intermittently rotatable element, held in bearings 12 at the top of the frame and extending beyond the frame at one side. The frames or carriages, as reciprocable elements, are thus suspended at opposite sides

of a rotatable element and are supported in mutually balanced condition. The frames are adapted to be alternately raised and lowered for disposing the mutually parallel rows of 5 long shank hooks 13, 14, attached to the lower ends of the frames, respectively below the casing 1 to receive the candles C, and above the casing 1 in a position for candle removal. The hooks 13, 14 traverse the dies 10 10, one of which dies is inserted in each tube 2 and locked therein by element 16 engaging the circumferential groove 17 at the bottom of the die. Each die is flanged at the top as at 19, and the bore of each is provided with a plurality of spaced circumferential substantially semicircular grooves 20. The bores of the dies are tapered upwardly, and the said grooves are provided adjacent the top or smaller diameter end of the 20 bore. The upper edge of the groove acts to scrape off surplus material, and the grooves function as circular pockets to temporarily receive and store the material until the candle leaves the die, after which the 25 melted material runs out of the groove downwardly through the bore, and preferably into a suitable drip receptacle placed beneath the chamber 1, said receptacle not herein being shown.

30 As before mentioned, the candles are placed upon the hooks after said hooks have traversed the dies and when the hooks are disposed below the chamber 1. Each frame, in this instance, carries a double row of 35 candles as a factor for capacity.

The frames are mutually balanced, each functioning as a counterbalance for the other and as candle carrying members, thus eliminating special counterbalancing 40 weights, and generally increasing operating efficiency.

The movement of the carriages is controlled electrically through both manually 45 and automatically operable switches, respectively as starting, and stopping or limit switches.

The shaft 11 at its outer end has the worm gear 30 meshing with a companion worm 31 mounted upon a motor shaft 33 of 50 a reversible, slow speed motor 32. The motor 32, in this instance, is mounted at the top of the machine upon a bracket 34 attached to a cross member 35, in which member the upper ends of the guide rods 3, 4 are stepped. The motor is operable by switches 55 in a manner hereinbefore disclosed, a detailed description of which switches and the electrical connections therefor, follows.

At one side of the casing 1 and disposed 60 in the path of each frame, are the limit switches 40, 41, respectively for the frames 8, 7, see Fig. 2. Each switch is engageable by the lower end of its respective frame, and serves to break or open the motor circuit to stop the motor. Below the switches

40, 41, in a convenient position, are disposed the starting switches 42, 43 operable for making or closing the circuit, to start the motor in reverse direction. The limit and starting switches control main line switches 70 having armatures respectively 50, 51. Limit switch 40 and starting switch 42 control the armature 50 of one main line switch, and the limit switch 41 and starting switch 43 control the armature 51 of the other main line switch. As shown in Fig. 2, when the frames are traveling in the direction indicated by the arrows a, b, the armature 50 is closed, and armature 51 open. When the bottom of the frame 8 engages the limit switch 40, the circuit will be broken, main line armature 50 will be released or opened, and the motor will come to rest. When it is desired to start the motor in a reverse direction, to draw the frame 8 upwardly and 75 lower frame 7, the button of the starting switch 43 is depressed to close the main line armature 51. A slow speed motor is used, so that the candles may be drawn at a relative slow rate of speed through the dies, 80 only so much of the motor circuit being herein shown as is necessary to an understanding of the operation. The main lines are indicated at 60, 61, the main line 60 being connected with the shunt winding 62 85 of the motor, the opposite terminal of the winding being connected by the conductors 63, 64, 65, respectively with the terminals 66, 67 of the main line switches having armatures 50, 51. The opposite 90 terminals 68, 69 of respective switches are connected with the main line 61, through conductors 70, 71. Conductors 72, 73 connect main line switch armatures 50, 51 with the motor armature terminals 75, 76. The armature 50 is controlled by the coil 80, one terminal of the coil being connected by the conductor 81 with one terminal of the limit switch 40. The other terminal of the coil 80 is connected by the conductor 82 with one terminal of the starting switch 43. The armature 51 is controlled by the coil 90, one terminal of which is connected by the conductor 91 with one terminal of the limit switch 41, the opposite terminal of the coil 90 being connected by the conductor 93 with one terminal of the starting switch 42. The opposite terminals of both starting switches are connected by the conductor 95 with the conductor 70, and the opposite terminals of both starting switches are connected by the conductor 96 with the main line 60.

With the frames positioned as shown in Fig. 2 and in movement as therein represented, current is being received through main line 60, shunt winding 62, conductors 63, 64, armature 51, conductor 73, terminal 75, through motor armature winding, not shown, terminal 76, conductor 72, armature

50 of the man switch to contact 68, conductor 70 to main line 61. The armature 50 of the main switch during this period is held as result of the energization of coil 80 by previous depression of the starting switch 43. When the bottom of frame 5 engages the limit switch 40 and breaks the circuit at that point, the main line switch 50 will be released or opened, and the frames

10 will come to rest.

A means is hereby provided whereby the starting of the machine may be manually initiated, and whereby the stopping of the same is automatically controlled. The 15 power is only used while the machine is operating, the power shaft being intermittently rotated in opposite directions conformable to motor reversal. By this arrangement current consumption is considerably reduced.

Having described my invention, I claim:

1. In a machine for finishing candles, finishing dies, means for drawing candles through said dies comprising mutually counterbalanced reciprocable members, and means for actuating said members.

2. In a machine for finishing candles, finishing dies, means for drawing candles through said dies comprising a reversible shaft having a sprocket wheel thereon, a sprocket chain engaged with said sprocket wheel, and two reciprocable frames adapted to support candles, suspended one at each terminal of said sprocket chain, and mutually counterbalanced at opposite sides of said shaft.

3. In a machine for finishing candles, a plurality of upright dies having upwardly tapered bores, means for drawing candles through the bores from below upwardly, said means comprising a reversible shaft, a flexible suspending element in driving connection with said shaft, reciprocable members at opposite sides of said shaft, one at each end of said suspending element, means upon each reciprocable member for attaching candles, said members being related to said dies in such manner that the candle attaching means of one frame, when 40 in their lowermost position, are projected within and below said dies, while the attaching means of the other frame are disposed a substantial distance above said dies.

4. A machine for finishing candles, having tubular finishing dies, means for drawing candles through said dies, comprising reciprocable members, and means for actuating said members, including an electrical motor, and a motor controlling switch engageable by said members for automatically stopping said motor.

5. In a machine for finishing candles, tubular finishing dies, means for drawing candles through said dies, comprising reciprocal frames, means for actuating said frames, including an electrical motor, motor controlling switches engageable by said frames for stopping the said motor, and manually operable motor controlling switches for starting said motor.

6. In a machine for finishing candles, tubular finishing dies, means for drawing candles through said dies, comprising a shaft having a sprocket wheel thereon, a reversible motor for alternately reversing shaft rotation, two reciprocable frames for supporting the candles, said frames suspended by a sprocket chain engaged with said sprocket wheel and mutually counterbalanced at opposite sides of said shaft, a motor controlling switch for each frame operable by its corresponding frame when in lowermost position, for stopping said frame, and switches for starting and controlling motor operation in reverse directions.

7. In a machine for finishing candles, a plurality of upright tubular upwardly tapered dies, means for drawing candles through the dies from below upwardly, said means comprising reciprocable members, means for actuating said members, including an electrical motor, motor controlling switches alternately engageable by said members for stopping the motor, and motor controlling switches manually operable for starting the motor in reverse directions.

8. In a machine for finishing candles, tubular finishing dies, means for drawing a candle through said dies, comprising a shaft, a reversible motor for alternately reversing and intermittently rotating said shaft, two reciprocable elements for supporting the candles in a position to be drawn through said dies, said elements suspended and mutually counterbalanced at opposite sides of a rotatable element upon and operable by said shaft, a motor controlling switch for each frame operable by respective frames for stopping said frames, and motor controlling switches for starting and controlling motor operation in reverse directions, to raise each frame from lowermost position.

In witness whereof, I hereunto subscribe my name, as attested by the two subscribing witnesses.

EVALD J. ENGMAN.
